UNITED STATES PATENT OFFICE.

ISAAC C. SHULER, OF AMSTERDAM, NEW YORK.

CONSTRUCTION OF SHEET-METAL COFFINS.

Specification of Letters Patent No. 24,635, dated July 5, 1859.

To all whom it may concern:

Be it known that I, ISAAC C. SHULER, of Amsterdam, in the county of Montgomery and State of New York, have invented sundry Improvements in the Manufacture of Sheet-Metal Coffins; and I do hereby declare that the following is a full, clear, and exact description of the same, reference being had to the accompanying drawing, which makes 10 a part of this specification and which represents a vertical longitudinal section of a sheet-metal coffin embracing my improvements.

I construct a box of sheet-metal of suitable 15 shape for a coffin. The sides (*a*) and the bottom (*b*) have their edges scrolled previous to their being locked together, thus forming what I shall call a double locked joint (*i*). The sides are pressed with bead 20 work (*e*) in panels, which beads are filled with fusible metal on the inside, for the double purpose of stiffening the sides, and of furnishing a convenient means by "peening," of taking out any accidental warpage 25 in the sheet metal. Around the corners of the bottom of the box on the outside I place an angular sheet-metal rim (*c*) forming a chamber all around the bottom, which may be filled with fusible metal, or left empty, 30 according to the size of the coffin. On the inside, and directly opposite the rim (*c*) is another angular rim (*d*) whose edges are bent against and soldered to the sides, in small coffins, but stand away from the sides 35 in large ones, leaving a channel or chamber which may be filled with fusible metal.

On the top of the walls of the box I set 40 a cast iron rim (*f*) extending outward and inward from the line of the sides, in which frame is a deep groove (*l*) which receives guides, and straightens the sheet metal of the sides. Between this frame (*f*) and the inside rim (*d*) pillars (*x*) are set up which 45 stiffen the sides, having an extended purchase against the protrusion of the rims, (*f*) and (*d*). In the top of the frame (*f*) is a groove all around.

To this coffin I have two covers (*h*) and (*j*). The under cover (*h*) has a cast metal 50 frame with a tongue on its underside, which frame stiffens the cover, while the tongue fits the groove in the upper surface of the frame (*f*), forming, when soldered, after the corpse is placed in the coffin, an air-tight joint. 55 This cover has a face-window, which is surrounded by an entire cast metal sash, (*m*)

which is fixed with screws or solder, or both. Outside of and above this cover is the cover (*j*) whose edges curve over the frame (*f*). This cover has a window and blind (*n*), corresponding to the window in the under cover (*h*), and serves the purpose of ornamenteally covering the fresh solder of the airtight joint before mentioned. The blind (*n*) is stiffened by means of an entire cast-metal frame (*o*), whereby it is hinged to the lid (*j*). From corner to corner diagonally across the bottom (*b*) are fixed braces (*k*) which serve to stiffen both the bottom and the sides. Thus formed, the coffin may be 70 grained or painted to taste, and trimmed within, by means of soldered strips of perforated tin.

Having thus described my improvements, 75 what I claim is:

1. The arrangement of stiffening the lower part of a sheet metal coffin, by locking together the scrolled edges of the sides and bottom, forming a firm rim when they are soldered together; substantially as described. 80

2. I am aware that I have before claimed stiffening the base of a sheet-metal coffin by filling with molten metal the surplus diameter of a tray in which the sides were set. I claim the sheet-metal rim (*c*) on the outside of the walls, as a means of stiffening the base, either with or without a filling of 85 molten metal, according to the size of the coffin.

3. I am aware that I have claimed stiffening the base of a sheet-metal coffin by means of a tray with scrolled edges fixed to the inside base. I claim the rim (*d*) of sheet metal, single or scrolled, forming an inside chamber, which may be filled with molten metal, or left hollow according to the size 95 of the coffin.

4. I am aware that I have claimed an entire cast metal frame resting on the flanged upper edge of the walls of a sheet metal coffin. I claim a cast metal rim (*f*) with a deep groove on the under side which receives, straightens, and stiffens the walls, and which serves to support the lids. 100

5. I am aware that I have claimed a certain arrangement of ribs. What I now claim is a different arrangement—namely setting the pillars or braces (*x*) at the corners and around the body of the coffin between the inward projections of the rims (*d*) and (*f*) which give them an extended purchase, for 105 the purpose of stiffening the walls, substan-

tially as described. I also claim the peculiar braces (k) to prevent the lateral racking of the bottom.

6. I claim the arrangement of pressing inverted beads or recesses, in any required number, in the sheet metal of the lid, walls, and bottom of a metal coffin on the inside and on the outside of the same, which may be filled with molten metal in the large size, 10 and left empty in the small size coffins, for the purpose of securing by a peculiar mode of manufacture of a level surface between the indented parts described.

7. The arrangement of fastening, firmly, 15 on the under side near the outer edge of the air-tight lid of a sheet metal coffin, a cast metal rim or its equivalent for the purpose of strengthening this lid and also for fitting into the groove in the rim (F) on the upper 20 edge of the walls of the coffin substantially as described.

8. The arrangement of fastening around the face-window, on the under side of the

air-tight lid of a sheet metal coffin, a cast metal sash or rim (M₁) which receives and 25 supports the face glass when it is cemented in its proper place.

9. I claim the arrangement of fastening permanently, on the under side near the outer edge of the sheet metal blind (M) 30 which covers the glass in the face window of a sheet metal coffin, a cast metal rim (O,) or its equivalent, for the purpose of strengthening and furnishing a means of securing the same to the outer lid which covers the 35 air-tight joints, substantially as described.

10. I am aware of having claimed various modes of covering the air-tight joint of the lid of a sheet metal coffin, both bisected and entire. I now claim the arrangement described, of two entire, distinct, separate sheet metal lids.
